SLIDE FASTENER

Egon Lustig, Prague, Czechoslovakia, assignor to
A. J. Rosenstein, Avon, Conn.

Application December 6, 1938, Serial No. 244,263

9 Claims. (Cl. 24—205)

My invention relates to slide fasteners.

It has among its objects to provide an improved slide fastener and further to provide such an improved fastener of the locking type whereby unintended opening movement of the slider is prevented. A further object of my invention is to provide such a fastener having improved locking means whereby, while obtaining an effective locking action, all necessity for providing a series of indentations or locking projections along the side walls of the slider is eliminated in such manner as markedly to simplify, and reduce the cost of, manufacture of the slider. A still further object of my invention is to provide an improved slider cooperating in an improved manner with the fastener elements carried by the stringers, this improved slider having improved guiding means disposed in an improved manner to cooperate with the fastener elements during movement of the slider, and to maintain the slider locked against unintended opening movement. Still another object of my invention is to provide such an improved slider having improved smooth guiding surfaces along its edges and cooperating in an improved manner with the fastener elements and with improved guiding surfaces on the central wedge to produce an improved construction operative to obtain an improved locking action while being freely operative to open or close the fastener and also adapted to be readily produced at small expense. These and other objects and advantages of my improved construction will, however, herein-after more fully appear.

In the accompanying drawing, I have shown for purposes of illustration, two embodiments which my invention may assume in practice.

In the drawing:

Figure 1 is a side elevation of a fastener equipped with one form of my improvement, the slider being shown in unlocked position ready to be moved up or down to close or open the fastener;

Fig. 2 is a view similar to Figure 1 but showing the slider in section, the top portion thereof being removed to facilitate illustration, and the parts being shown in locking position;

Fig. 3 is a detailed side elevation of the slider shown in Figure 1;

Fig. 4 is a detailed sectional view on line 4—4 of Figure 1, of the slider, and

Fig. 5 is a view similar to Figure 2 showing a modified construction.

Referring first to the construction shown in Figures 1 to 4, it will be noted that I have shown

5 a plurality of stringers 1 carrying cooperating fastener elements 2 of usual construction; the connection and disconnection of these elements 2 being controlled by a slider, generally indicated at 3, and of improved construction hereinafter fully described.

This slider is, in certain respects, of usual construction. Thus, as in usual practice, it comprises back and front elements 4 and 5, preferably bent 10 out of a single piece of metal and having a connection 6 therebetween so that they are disposed in parallel relation with a space 7 therebetween through which the cloth of the stringers 1 extends in such manner as to permit movement of the slider 3. Further, as usual, the portions 4 and 5 are connected together by a riveted connection including a central guide or wedge 8 riveted at one end to the back slider portion 4 and having a connected portion 9 on the outside of the front slider portion 5 to which is connected a pull member 10 of usual construction. Further, each of the portions 4 and 5 is provided with spaced and parallel, straight inside walls 11 at the bottom of the slider and a portion above these 15 straight walls 11 extending upward and outward on opposite sides of the central guide or wedge 8.

20 In my improved construction, however, it will be noted that each of the members 4 and 5 is provided with improved side walls 12 which form a continuation of the straight walls 11, these side walls herein being of an improved construction. Thus, as distinguished from having upper side walls which extend in Y form, i. e. at an acute angle to the vertical from the upper ends of the side walls 11 and which, further, are each provided with a series of indentations on their inner faces, these walls 12 are herein curved outwardly and upwardly, and, furthermore, are smooth. More particularly, it will be observed that from the upper ends of the walls 11, the walls 12 are concave and curve gradually outwardly and upwardly in an arc and in such manner that the upper end portion 13 of each wall 12, while curved slightly inwardly is substantially parallel with the axis of the slider, herein indicated by the line 4—4 of Figure 1. As shown, each end portion 13 is also of greater length than the depth, or thickness, of a fastener element as measured along the stringer, and a transverse, and herein slightly downwardly and outwardly inclined, abutment 14 is provided at the upper end of each wall 12. Further, it will be noted that the guiding member or wedge 8 is not disposed above this extremity 14 of these walls 12; the wedge member, instead, being so disposed

that its guiding surfaces 15 are wholly below the upper end of the surfaces 13. Here, preferably, these guiding surfaces 15 are also curved, the same in this form of my invention being convex and struck from the same axis as the curved walls 12 and portion 13 in such manner as to produce for each set of fastener elements a guiding passage having concentric walls.

In the use of my improved construction, it will be evident that in normal closing and opening movements of the slider 3, the fastener elements 2 will be connected and disconnected with facility as the guide 8, and walls 12 including their portions 13, of the slider are moved up or down relative to the fastener elements 2. Attention is, however, directed to the fact that in these movements of the slider, the elements 2 in passing between the guiding surfaces 15 on the guiding member 8 and the guiding surfaces 12 on the portions 4 and 5 of the slider, will conform somewhat to the curvature of the surfaces 15, 12, and 13, i. e. move outward and upward in the curved paths indicated. Thus, it will be observed that, as shown in Figure 1, these fastener elements 2 which are opposite the upper portions 13 of the surfaces 12, will normally have their outer ends moving freely over these portions 13. Consequently, in my improved construction the slider 3 will function to close or open the fastener elements in a satisfactory manner. However, it will be observed that the upper end portions 13 are enabled to cooperate with the adjacent end surfaces of the fastener elements 2 in such manner as to produce a wholly new and effective locking action when the upper end of either stringer is pulled laterally. More particularly, reference is here made to Figure 2, and to the fastener elements 2 on the right hand stringer element 1 which are below and above the top 14 of the slider portion 13, attention being directed to the fact that when this stringer 1 is pulled slightly laterally as indicated, these elements 2 function with the portion 13 and upper face 14 on the slider, and with the wedge surfaces 15, in an improved manner to effect locking. Thus, if the right hand stringer 1 is pulled even slightly to the right, as shown in Figure 2, in a manner which would result in an automatic downward or opening movement of the slider in previous constructions, it will be noted that, herein, the outer end surface 16 of the element 2 just below the top face 14 will be tilted to the right in such manner as to engage the inside face of the portion 13, while, as a result of the tilting movement on the stringer 1, the fastener elements 2 thereon below the portion 13 will be pressed inward into engagement with the adjacent wedge surface 15, all in such manner as thereby effectually to prevent automatic downward movement of the slider 3. Further, it will be observed that the upper fastener element 2, i. e. that above the top face 14, by reason of the lateral deflection of the stringer 1 previously mentioned, will also be so displaced laterally as to engage and laterally project over the upper end face 14, this upper edge 14 then forming a fulcrum about which the upper element 2 also tilts in such manner as further to increase the inwardly directed pressure of the lower elements 2 against the wedge surface 15. Thus, lateral movement of the stringer 1 will cause wedging of the portion 13 in the space between the two adjacent fastener elements 2 and the portions 13 and 14 on the slider will so engage different portions of the extremities of the two adjacent fastener elements 2 and so press

laterally the lower fastener elements 2 against the wedge surface 15, as effectually to lock the slider against accidental movement as a result of lateral movement of either stringer. Referring next to the stringer 1 at the left in Figure 2, it will be noted that the fastener element 2 adjacent the portion 13 on the left hand face 12 is so tilted by the lateral movement of the stringer 1 indicated, that the outer end 16 of this element 2 will also engage the portion 13 and thereby also force the lower elements 2 against the wedge surface 15, in such manner as to exert a like locking action. Thus, the portions 13 on both sides of the axis of the slider cooperate in effecting locking.

It will, of course, also be evident that a locking action will be obtained on each side of the slider when the surfaces 16 are in any of the various possible positions between the extreme positions illustrated, the extreme bottommost position on the portion 13 being shown at the right in Figure 2, and the extreme top position being shown at the left, wherein the surface 16 is just about to pass off of the portion 13. Thus, obviously, my improved construction, in addition to providing effective locking, provides a relatively long effective locking area or portion 13 at the top of each wall 12, all while enabling all of the inside surfaces of wall 12, including the portion 13 to be smooth from end to end and eliminating any necessity for the use of any indentations or irregularities. Further, it will be evident that when the parts are thus locked, the slider 3 may be moved downward freely whenever desired, and that, when the same is moved upward, the end portion 14 will force any fastener element 2 which overlies the same, out of its path and toward the axis of the slider until the parts assume the relation shown in Figure 1.

In Figure 5, I have shown a modified construction wherein it will be noted that the principal difference is that the guide or wedge 8 is located higher relative to the upper portion 13 on the surfaces 12, but still below the upper ends of the latter. Further, it will be noted that herein this portion 8 is somewhat smaller than the portion 8 heretofore described so that the elements 2 do not necessarily move outward in a curve so closely conforming to the surfaces 12. Nevertheless, it will be noted that by reason of the fact that the portions 13 are here also so inwardly directed and shaped as heretofore described, generally similar locking action is obtained; the end surface 16 of any element 2 immediately below the upper end surface 14 being tilted in such manner as to force inward into engagement with the wedge surface 15, the adjacent lower elements 2 and thereby lock the slider substantially as previously described. Further, it will be evident that the fastener element 2 above the tilted element 2 will similarly overlie and abut the upper edge portion 14 to produce a wedging or cramping locking action similar to that previously described.

While I have in this application specifically described two embodiments which my invention may assume in practice, it will be understood that the same are shown for purposes of illustration, and that the invention may be modified and embodied in various other forms without departing from its spirit or the scope of the appended claims.

What I claim as new and desire to secure by Letters Patent is:

1. In a slide fastener, a slider having outer

guiding means including diverging portions, stringers having cooperating fastener elements thereon guided by said guiding means and also having spaces between adjacent elements, and slider locking means for engaging and locking an element when a stringer is pulled laterally comprising a relatively inwardly and upwardly directed prolongation on one of said diverging portions and extending above the upper end of the latter and having on said prolongation an inner elongated guiding and locking surface at least as long as the space between said elements and conforming generally to the normal path of the outer ends of adjacent elements in the top of the slider.

2. In a slide fastener, a slider having outer guiding means including diverging portions, stringers having cooperating fastener elements thereon guided by said guiding means and also having spaces between adjacent elements, and slider locking means for engaging and locking an element when a stringer is pulled laterally comprising relatively inwardly and upwardly directed prolongations of said diverging portions and extending above the upper ends of the latter and having on said prolongations inner elongated guiding and locking surfaces at least as long as the space between said elements and said elongated surfaces being generally concave and closer to one another at their upper ends than at their lower ends.

3. In a slide fastener, a slider having outer guiding means including diverging portions, stringers having cooperating fastener elements thereon guided by said guiding means and also having spaces between adjacent elements, and slider locking means for engaging and locking an element when a stringer is pulled laterally comprising a relatively inwardly and upwardly directed prolongation on one of said diverging portions and extending above the upper end of the latter and having on said prolongation an inner elongated guiding and locking surface at least as long as the space between said elements and conforming generally to the normal path of the outer ends of adjacent elements in the top of the slider, the diverging portion carrying said prolongation being concave and said elongated surface likewise being concave and merging into and substantially continuing the curvature of said diverging portions.

4. In a slide fastener, a slider having inner wedging means and cooperating outer guiding means, the latter including diverging portions, stringers relatively movable between said wedging means and outer guiding means and having cooperating fastener elements thereon, and means comprising relatively inwardly and upwardly directed prolongations of said diverging portions and having on said prolongations inner elongated guiding and locking surfaces extending into the path of an element below the upper extremities of one of said prolongations when either stringer is pulled laterally, for tilting said element into locking engagement with one of said surfaces and pressing other still lower elements on the stringer into engagement with said wedging means.

5. In a slide fastener, a slider having outer guiding means including diverging portions, stringers having cooperating fastener elements

thereon guided by said guiding means and also having spaces between adjacent elements, and slider locking means for engaging and locking an element when a stringer is pulled laterally comprising relatively inwardly and upwardly directed prolongations of said diverging portions and extending above the upper ends of the latter and having on said prolongations inner elongated guiding and locking surfaces spaced apart a distance slightly less than the greatest distance between said outer guiding portions.

6. In a slide fastener, a slider having inner and cooperating outer guiding means including diverging portions, stringers having cooperating fastener elements thereon guided by said guiding means and also having spaces between adjacent elements, and slider locking means on the upper ends of said diverging portions comprising relatively inwardly and upwardly directed prolongations of the latter normally guiding said fastener elements and extending, when a stringer is pulled laterally, both into one of said spaces and into the path of the fastener element below said space, said prolongations having inner guiding surfaces approaching parallelism to one another and also having downwardly and outwardly sloping top abutments cooperating with said guiding surfaces to form wedges receivable in said spaces when stringers are pulled laterally.

7. In a slide fastener, a slider having outer guiding means movable along and controlling the connection of fastener elements spaced longitudinally on flexible stringers, said slider having diverging outer guiding portions, and slider locking means on the upper end of one of said diverging portions comprising a relatively inwardly and upwardly directed prolongation of the latter and having on said prolongation an inner elongated guiding and locking surface at least as long as the space between said elements and conforming generally to the normal path of the outer ends of adjacent elements in the top of the slider.

8. In a slide fastener, a slider having an inner wedge and cooperating outer guiding means movable along and controlling the connection of fastener elements spaced longitudinally on flexible stringers, said slider having diverging outer guiding portions extending below said wedge, and slider locking means on the upper ends of said diverging portions comprising relatively inwardly and upwardly directed prolongations of the latter extending above the bottom of said wedge and having on said prolongations inner elongated guiding and locking surfaces at least as long as the space between said elements and said surfaces being generally concave and closer together at their upper ends than at their lower ends.

9. In a slide fastener, a slider having outer guiding means movable along and controlling the connection of fastener elements spaced longitudinally on flexible stringers, said slider having diverging outer guiding portions, and slider locking means on the upper ends of said diverging portions comprising relatively inwardly and upwardly directed prolongations of the latter and having on said prolongations inner elongated guiding and locking surfaces spaced apart a distance slightly less than the greatest distance between said outer guiding portions.

EGON LUSTIG.
